UNITED STATES PATENT OFFICE.

BRAYTON G. RICHARDS, OF CHICAGO, ILLINOIS, ASSIGNOR TO JACQUES ROUSSE, OF LOS ANGELES, CALIFORNIA.

TOWEL-RACK.

1,372,311.

Specification of Letters Patent. Patented Mar. 22, 1921.

Application filed February 24, 1920. Serial No. 360,924.

To all whom it may concern:

Be it known that I, BRAYTON G. RICHARDS, a citizen of the United States, and a resident of the city of Chicago, county of Cook, and State of Illinois, have invented 5 certain new and useful Improvements in Towel-Racks, of which the following is a specification.

My invention relates to improvements in 10 towel racks and has for its object the provision of a simple and effective construction of this character arranged to prevent the unauthorized removal or misuse of towels, which is of simple construction and 15 efficient in operation.

Other objects will appear hereinafter.

The invention consists in the combinations and arrangements of parts hereinafter described and claimed.

20 The invention will be best understood by reference to the accompanying drawings forming a part of this specification, and in which,

Figure 1, is a front view of a towel rack 25 embodying the invention,

Fig. 2, a transverse vertical section of the same,

Fig. 3, a front view of a modified form of construction, and

30 Fig. 4, a vertical transverse section of the construction shown in Fig. 3.

The form of construction illustrated in 35 Figs. 1 and 2 comprises a suitable supporting frame or cabinet 5 having a clean towel supporting shelf 6 arranged at an elevated position, as indicated, and a soiled towel receptacle 7 arranged under said shelf, as shown. A towel guide rod 8 has its upper end releasably secured in a lock 9 positioned

40 in the back of the frame 5 just above the upper surface of the shelf 6, said rod extending thence above, adjacent and substantially parallel to the upper surface of the shelf 6 and outwardly beyond the outer

45 edge thereof, extending thence downwardly and rearwardly into the receptacle 7, as shown, and constituting a suitable guide for the towels 10, as will be readily understood.

The clean towels 10 are arranged in a stack 50 or pile on the shelf 6 and over the horizontal portion of the rod 8, said towels being provided with gromets 11 threaded on the rod 8. The horizontal portion of the rod is positioned closely adjacent the upper sur-

55 face of the shelf 6, whereby the edges 12

beyond the gromets 11 are in contact with, or in close proximity to the upper surface of the shelf, and whereby the outer end of the horizontal portion of the rod 8 is reinforced and stiffened against downward 60 bending. In this way, it will be observed that while the extending edge 12 of a single towel would perhaps furnish little or no stiffening for the rod 8, the plurality of such edges will furnish material bracing 65 and stiffening of said rod to prevent downward sagging of the same and undue strain on the lock 9. Furthermore, it will also be observed that any material or extended downward sagging or movement of the 70 outer end of the horizontal portion of the rod 8 will bring the gromets 11 in close proximity to or contact with the shelf 6, thus furnishing a rigid and positive brace for said rod against downward pressure 75 thereon, and that the more towels piled on top of the rod the greater this stiffening and bracing action will be.

The modified form of construction illustrated in Figs. 3 and 4 is identical with that 80 already described, except that the back of the frame or cabinet is terminated just above the lock 9, and the upper edge 5' of said back thus forms a transverse supporting bar over which the stack or pile of 85 towels 10 may be thrown, as indicated in Fig. 4. This arrangement relieves the horizontal portion of the rod 8 of a large portion of the weight and strain of the stack of towels, and also permits of the use of a larger 90 number of towels if desired. This device is also capable of use with the towels arranged as indicated in Fig. 2, if desired, but it is not quite so attractive in appearance as the latter construction.

95 While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

100 Having described my invention, what I claim as new and desire to secure by Letters Patent is:—

1. A towel rack comprising a towel supporting shelf; a guide rod extending out-

110

wardly over, in close proximity to, and substantially parallel to the top of said shelf, the proximity of said guide rod being such that towels may rest over said rod with their sides supported by said shelf in substantially flat condition and the outer perforated edges of said towels be turned downwardly to slide upon said rod and to make contact with the top of said shelf upon the downward sagging of said rod, substantially as described.

2. A towel rack comprising a towel supporting shelf; and a guide rod extending outwardly over, in close proximity to, and substantially parallel to the top of said shelf beyond the outer edge thereof and thence downwardly and rearwardly under said

shelf, the proximity of said rod to said shelf being such that towels may be rested over said rod with their sides supported by said shelf in substantially flat condition, and the outer perforated edges of said towels be turned downwardly to slide upon said rod and to make contact with the top of said shelf upon the downward sagging of said rod, substantially as described.

In testimony whereof I have signed my name to this specification in the presence of two subscribing witnesses.

BRAYTON G. RICHARDS.
